Fig. 2

Fig. 3

Fig. 1 is a front elevational view of a spectacle frame embodying my new design;

Fig. 2 is a top plan view thereof; and

Fig. 3 is a side elevational view thereof.

The temples are shown broken away in Figs. 2 and 3 for purpose of convenience.

The drawing is shaded to indicate contrast in color.

The characteristic features of my new design are shown in full lines in the drawing.

I claim:

The ornamental design for a spectacle frame or the like, substantially as shown and described.
